UNITED STATES PATENT OFFICE.

FRIEDRICH GEGAUF, OF NEWARK, NEW JERSEY, ASSIGNOR TO HERMAN BORNEMANN, OF SAME PLACE.

HOLDING-FRAME FOR EMBROIDERING-MACHINES.

SPECIFICATION forming part of Letters Patent No. 388,035, dated August 21, 1883.

Application filed June 16, 1886. Serial No. 205,302. (No model.)

To all whom it may concern:

Be it known that I, FRIEDRICH GEGAUF, a citizen of Germany, residing at Newark, in the county of Essex and State of New Jersey, have 5 invented certain new and useful Improvements in Embroidering Machines and Attachments; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

This invention relates to improvements in 15 attachments for embroidering-machines, particularly those known as the "Swiss" embroidering-machines, to which, however, the application of the invention is not necessarily limited, and is designed to enable a large number 20 of small patterns on separate pieces of material to be embroidered on the same machine simultaneously.

The invention is further intended to be used 25 outside of and independent from the said embroidery-machine as a hand embroidering-frame, like an ordinary tambour-frame, both of which uses, however, will be more fully described hereinafter.

In the accompanying three sheets of drawings, in which similar letters of reference indicate corresponding parts, Figure 1, Sheet 1, is a front elevation of that portion of an embroidering-machine in which the material to be embroidered is arranged and which is caused 30 to move or vibrate in front of the needles and of my attachment arranged therein. Fig. 2 is a side elevation of an embroidering or stretching frame and portions of its holding-strip detached from the vibrating frame. Fig. 3 is a 35 section of Fig. 2 through line x . Fig. 4 is a perspective view of a stretching-frame and binding-clamps. Fig. 5 is a transverse section of a stretching or embroidering frame and the material secured thereto. Fig. 6 is a cross- 40 section of one side of the frame shown in Fig. 5, illustrating the manner of applying the binding-clamps thereto. Fig. 7 is a side elevation of a modified form of binding clamp. On Sheet 2, Figs. 8, 9, and 13 illustrate various 45 forms of frames. Figs. 10 and 12 are front and end elevations, respectively, of a form of

frame differing in cross-section from those above described; and Fig. 11 illustrates various cross-sections that may be used. Fig. 14 on Sheet 3 is a front elevation of an embroidering-machine with which my improvement is adapted to be used. 55

Similar reference-letters are employed to indicate corresponding parts.

The special purpose for which this invention 60 is designed when used in an embroidering-machine is to enable a large number of patterns of varying sizes to be embroidered on separate pieces of cloth or other material instead of embroidering the patterns on a continuous piece of material wound on rollers, and wound and unwound as the designs are finished and a new surface is presented to the needles. This is particularly advantageous in 65 embroidering handkerchiefs, patterns for slippers, &c., and all articles or garments that are embroidered after having been cut to a pattern or any desired size—as towels, napkins, &c.

The portion of an embroidering-machine in 75 which the improved attachment may be used (shown in Figs. 1 and 14) is a vibrating frame, A, to which the material to be embroidered is suitably attached, and which, by the movement of said frame, is caused to present new 80 surfaces to the needles. In said frame are arranged the fabric-holding frames B, which are placed close together between adjustable strips C C', two pairs of which are shown in Fig. 1—one pair for each row of needles used in the 85 Swiss machine. For adjusting said strips C C' any suitable mechanical device may be employed, that shown in the drawings for illustration consisting of threaded rods c , which extend from the top to the bottom of the frame 90 A, as indicated, and through the strips, and are provided with nuts c' above and below each strip, which, when turned, cause the raising and lowering of each strip as far as may be desired. The adjustability of the strips allows the insertion of embroidering-frames of different sizes 95 therebetween in the same machine.

To secure the embroidering-frames firmly between the strips, a groove, c'' , is provided in one of said strips and a recess, c''' , in the other 100 of said strips, as indicated in Figs. 2 and 3, one end of the embroidering-frames resting in

the groove and the other end thereof being held in the recess by a pivoted arm, c^4 . The frames are removed from the strips simply by turning the arm c^4 , and are thereby free to be 5 lifted from the groove and clear of the strips. To separate the frames when placed in position between the strips, I may employ projections c^5 , which prevent the frames from being displaced, as indicated in Fig. 2; but the frames 10 may also touch and support one another without the intervening projections, particularly when frames of different widths are used.

In the drawings various kinds of embroidery-frames are shown, which may have three, 15 four, or any number of sides, being triangular, quadrilateral, or polygonal in form or irregularly formed, Figs. 8 and 9, but all of which sides are preferably straight to allow of the application and proper operation of the spring- 20 clamps d .

In cross section the sides may be of any form, either round, elliptical, slightly flattened, or angular, as at e' , e , and e^2 , Fig. 11, respectively, that shown at e in said figure being considered 25 preferable because of the ease with which the binding-clamps d may be applied thereto and caused to bind the goods firmly to the frame.

In Figs. 4, 5, and 6 the method of applying the clamps to the embroidery-frame and of 30 drawing the material to be embroidered tightly across the frame is illustrated, when the sides of the frame are formed in cross-section, like the form shown at e , Fig. 11. The clamps shown in said figures are formed from a continuous piece of spring metal bent substantially as shown, and, in applying the same to the stretching-frame, are pushed upon the frame from the sides over the fabric, as indicated in Figs. 4 and 6, and are then turned 35 down at right angles to the first position, as in Fig. 5, the fabric f being stretched between the inner edges, d' , of the clamps.

The sides of the frame B being oval or elliptical in cross-section, as shown in Fig. 6, 40 the clamps are readily pressed upon the same from the sides over the thin edges, and when turned down at right angles to the first position, the increased diameter of the oval sides causes the clamps to bind upon the 45 frame and to hold the fabric securely upon said frame. This method of applying the clamps to the stretching-frame may also be used when the sides are angularly formed in cross section, as at e^2 , Fig. 11.

50 In Figs. 16 and 12 is illustrated a stretching-frame, the sides of which in cross-section are round, as at e' , and the binding-clamps are applied thereto by being slid or pushed on the end of each side, as shown in Fig. 10.

55 As hereinbefore mentioned, the embroidery or stretching frames may be variously shaped quadrilaterally, as in Figs. 1 to 10, which form is especially adapted for embroidering the centers of handkerchiefs, &c.; or said frames may be irregularly formed, as shown 60 in Figs. 8 and 9, and thereby adapted for embroidering the corners of handkerchiefs, &c.,

because of the peculiar form. These irregular forms are advantageous in that when arranged side by side, as indicated in Figs. 8 and 9, in 70 the vibrating frame a larger number of the frames may be inserted in the same space when thus irregularly formed than when quadrilaterally formed, the irregular forms fitting one into the other, as illustrated in said figures. 75

While the embroidery-frames herein described are intended and adapted to be used in an embroidery-machine, still they may be employed as a hand embroidery-frame. When designed for this purpose, any regular 80 form of frame may be used, those previously described or the form illustrated in Fig. 13.

In Fig. 1 is illustrated a modified form of the binding-clamp, consisting of two pivoted sections, d^2 d^3 , between which is arranged a 85 spring, d^4 , which provides the force necessary to bind the fabric upon the stretching-frames.

Having thus described and illustrated my invention, what I claim is—

1. A fabric-stretching frame provided with 90 sides oval in cross-sections, in combination with binding-clamps having yielding jaws applied to the thin edges of said oval sides and turned at right angles thereto, so that said clamps bind the ends of the oval sides of said frame, for the purposes set forth.

2. The combination, in a vibrating or tambour frame, of pairs of grooved and recessed holding-strips adjustably arranged in said frame, with threaded rods secured to said frame 100 on which said holding-strips move, and holding-nuts arranged on said rods and engaging with the said holding-strips, substantially as and for the purposes set forth.

3. The combination, in a vibrating or tambour frame, of pairs of holding-strips constructed and arranged to hold a series of removable fabric-stretching frames, said stretching-frames projecting or fitting one into the other, and binding-clamps, whereby the corners 110 of the fabric to be embroidered are held upon and stretched across said frames, substantially as and for the purposes set forth.

4. The combination, with a vibrating or tambour frame of an embroidery-machine, of 115 pairs of adjustable holding bars or strips extending longitudinally in said frame, and constructed and arranged to hold a series of fabric-stretching frames removable therein and to be moved toward and from each other, adjusting devices, whereby said pairs of bars are moved toward and from each other and are held rigidly in position when thus adjusted, and a series of fabric-stretching frames 120 removably arranged between said holding-bars, 125 for the purposes set forth.

In testimony that I claim the foregoing I have hereunto set my hand this 5th day of June, 1886.

FRIEDRICH GEGAUF.
